UNITED STATES PATENT OFFICE.

CHARLES W. KECKLER, OF NEWARK, NEW JERSEY, ASSIGNOR TO WESTERN ELECTRIC COMPANY, INCORPORATED, OF NEW YORK, N. Y., A CORPORATION OF NEW YORK.

TELEPHONE SYSTEM.

Application filed March 27, 1918. Serial No. 224,925.

To all whom it may concern:

Be it known that I, CHARLES W. KECKLER, a citizen of the United States, residing at Newark, in the county of Essex, State of New Jersey, have invented certain new and useful Improvements in Telephone Systems, of which the following is a full, clear, concise, and exact description.

This invention relates to telephone systems and more particularly to signaling means therefor and to trunking arrangements between an intercommunicating telephone system and an exchange system.

One object of the present invention is to enable a single piece of apparatus to be used as a signal when included in a signaling circuit and also as an impedance means on establishment of the talking connection of the apparatus with which it is associated. In accordance with this feature, a signal, operable on direct current, is associated with a telephone set for normal signaling operation, and arranged for inclusion in the talking circuit of such set under certain conditions to serve as an impedance means for talking current supplied to such set on establishment of a talking connection therewith.

Another object is to provide a new and improved trunking arrangement between one or more local telephone stations and an outside line or exchange, in which a trunk line can be held during conversation and also during the temporary disconnection or the transfer of a call from one local station to another without giving a disconnect signal at the exchange. In accordance with this feature of the invention, a trunk circuit, provided with two ends inductively connected, extends from the local station to the distant station or exchange and is provided with a bridging connection across one end of the trunk line and with means, operated by telephonic association of a local station with the other end of the trunk line, to control the bridging connection.

Another object is to provide a telephone system in which the signal of a local station in telephonic communication with another local station or with a trunk line will be operated upon such station being called by another local station and in accordance with another feature of the invention the signals of the local stations are so arranged that an

operating circuit therefor will be established in the usual operation of calling such station even though the called station be already connected with another local station or with the trunk line.

Other objects and features of the invention will appear from a consideration of the following description.

In the drawing, which represents an embodiment of the invention as applied to an intercommunicating system provided with a trunk connection to a common battery exchange, three stations of the intercommunicating system are shown, together with a trunk line extending therefrom to an exchange at which the jack 10 and answering signal 11 of the trunk are located.

The intercommunicating stations are each provided with a transmitter 12, receiver 13, hook switch 14, and signal 15, which in addition to serving as a signal acts as an impedance means through which talking current is supplied to its respective station when the latter is called by and secures a talking connection with another intercommunicating station of the system. These stations are provided with keys such as A, B, C and H which enable interconnection between such stations, and such stations as are equipped for trunk service also have a trunk key T, as well as a retaining key R if they are to be able to prevent the operation of the disconnect signal at the exchange on the transfer of a trunk call to another station of the system.

The keys with the exception of the home keys H have three positions: the normal position, as shown; the way-down position, which is the signaling position for all but keys R and T and in which position the upper pair and the lower pair of contacts are engaged and where the third contact engages the bus bar 16; and an intermediate position which is the same as the way-down position except that there is no engagement with the bus bar 16. The home keys H need have only a normal and an intermediate position since it is not necessary that any of the contacts thereof engage the bus bar 16 under any conditions. A spring-held locking plate 17 serves to hold any key, once depressed, against release until another key is operated, but permits any key depressed to way-down position to assume its intermediate position.

ate position as soon as pressure thereon is removed.

To illustrate the operation of the system, assume that station A desires to communicate with station B. Key B at station A is depressed to signaling position, thereby operating the signal 15 at B over a circuit extending from signaling battery 18, conductors 19 and 20, bus bar 16, third contact of key B, conductor 21, line conductor 22 of station B, conductors 23 and 24, normal contact, armature and lower winding of signal 15, and conductors 25 and 26 to the other side of battery 18. The signal 15, in operating, interrupts its circuit and is deenergized, but the armature on retraction immediately closes this circuit and the armature is again attracted, thereby again opening its circuit. This action will continue so long as key B is maintained in signaling position or until station B responds by removing the receiver from the switchhook 14. The key B on being released from signaling position assumes its intermediate position and the receiver at station A, having been removed from the switchhook thereat, is placed in communication with B upon the latter removing his receiver and depressing his home key H to intermediate position. A circuit is thus completed, extending from talking battery 27, conductors 28 and 29, upper winding signal 15 at B, lower alternate contacts of switchhook 14, conductor 30, first and second contacts of key H at B, conductors 31 and 32, upper alternate contacts of switchhook 14, receiver 13, transmitter 12, conductors 33 and 34, fourth and third contacts of key H, conductor 23, middle alternate contacts of switchhook 14, conductor 35, lower winding of signal 15, and conductors 25 and 26, to the other side of battery 27. Station A is connected in parallel with this circuit beginning at conductor 30, and extending over line conductor 36, conductor 37, first and second contacts of key B at station A, conductor 38, upper alternate contacts of switchhook 14, receiver 13, transmitter 12, conductor 39, fourth and third contacts of key B, and conductors 21 and 22 to conductor 23. The windings of the signal 15 at the called station B thus serve as impedance means for talking current supplied to the connected stations A and B; and while the armature of the signal 15 at the called station will be attracted under these conditions, it will not vibrate, inasmuch as a short circuit is provided about the armature contact upon the removal of the receiver at B. This short circuit extends from the connection of the conductors 23 and 24, through the middle contacts of the switchhook 14, and conductor 35 to the junction of the armature connection therewith. Conversation can now take place in the usual manner.

It is often desirable that a party at one local station already connected with another local station be apprised of any attempt by a third local station to connect with the first station while thus connected, and in the circuit arrangement shown the calling party would receive such an indication. To illustrate: Assume C calls A. Depressing key A at station C completes a circuit through the lower winding of signal 15 at station A; this circuit extending from battery 18, conductors 19, 40, bus bar 16 and third contact of key A at station C, conductors 41, 42, 43 and 44, normal contact, armature and lower winding of signal 15 at station A, and conductors 45 and 26 to the other side of battery 18. The armature of signal 15 is thereby attracted but gives only a single tap to the gong thereof due to a short circuit about the armature and its contact extending from the connection of conductors 43 and 44, through middle contacts of switchhook 14, and conductor 46 to the connection of the armature therewith. The single tap given by the signal 15 serves to indicate to A that another local station desires to obtain connection with station A. As soon as key A at station C is released from signaling position the signaling circuit is opened and the signal at station A returns to its normal position.

When A and B complete conversation they will restore their receivers to their respective switchhooks, thereby opening the talking circuit therebetween at the switchhooks, while the key B at station A and key H at station B will be released to normal position on depression of another key at its respective station, thus restoring the apparatus associated with stations A and B to normal condition.

Referring now to the trunking operation of the system, assume that station A desires to make a trunk call. The trunk key T thereat is depressed to intermediate position. A circuit is thereby established extending from local trunk talking battery 47, right-hand winding of relay 48 (also serving as an impedance means), conductor 49, trunk conductor 50, conductor 51, fourth and fifth contacts of key T at station A, conductor 39, transmitter, receiver, and upper contacts of switchhook, conductor 38, second and first contacts of key T, conductors 52, 53 and 54, and left-hand winding of relay 48 to the other side of battery. Condensers 55 and 56 are arranged in the respective trunk conductors 50 and 53 to prevent flow of direct current from the battery 47 to the exchange, but the operation of relay 48 closes a circuit to bridge a relay 57 across the exchange side of the conductors 50 and 53 and completes a circuit to actuate the answering signal 11 at the exchange. This circuit extends from signaling battery 58, normal ring contact of jack

10, conductor 53, armature and alternate contact of relay 48, conductor 59, winding of relay 57, conductor 50, normal tip contact of jack 10, and signal 11 to the other side of battery 58. Signal 11 is thereby actuated and the exchange operator responds by plugging in at the jack 10 in the usual manner, thereby disconnecting the answering signal 11 from the trunk line. The operator extends the line to the called party in the usual manner, and conversation takes place between station A and the called party in the usual manner, talking battery (not shown) being supplied to the exchange end of the line on the operator's answering the call. The condensers 55, 56 permit the passage of the fluctuating voice currents between the exchange and intercommunicating ends of the trunk line and enable local talking battery 47 to be supplied at the intercommunicating end of the trunk, thereby providing more uniform and improved transmission than where talking current for intercommunicating stations connected with the trunk line is supplied from the exchange.

Should an outside line call the trunk associated with the intercommunicating system, the operator would plug into the jack 10 and apply signaling current to operate the trunk signal 60, which signal is preferably located in proximity to a local station charged with the duty of answering trunk calls. On perceiving the operation of the signal 60, the party, for example, at station A, removes the receiver and depresses the trunk key T to intermediate position, thereby establishing talking connection with the trunk line, but without operating the signal 11, since this is disconnected on the operator plugging into the jack 10. If station A is the desired station, conversation now takes place in the usual way, but if the calling party desires to talk with station B, the party at A retains the receiver off the switchhook and depresses retaining key R to way-down position, thereby completing an energizing circuit for a holding relay 61. This circuit extends from battery 18, conductors 26 and 62, resistance 71, winding of relay 61, conductors 63 and 64, third contact of key R, bus bar 16, and conductors 20 and 19 to the other side of battery 18. Relay 61 operates, completing a holding circuit for itself extending from battery 18, conductors 26 and 62, resistance 71, winding left-hand armature and alternate contact of relay 61, conductor 70, left-hand armature and alternate contact of relay 57 (still energized) and conductors 65 and 19 to the other side of battery 18. The operation of relay 61 also provides a circuit connection for the relay 57, to bridge it across the trunk conductors independent of the alternate contact of relay 48. This connection extends from conductor 50, winding

of relay 57, conductors 59 and 66, right-hand armature and alternate contact of relay 61 to conductor 53.

The depression of key R returns key T to normal position, and in order to prevent any possibility of relay 48 being deenergized and opening the circuit of relay 57, thus giving a disconnect signal at the exchange before the relay 61 could be operated to complete the holding circuit for relay 57, the first, second, fourth and fifth contacts of key T are multiplied respectively to the same contacts of key R. Relay 57 is thus retained energized and effectually prevents a disconnect signal being given at the exchange at this time. The party at A now depresses key B, thereby releasing key R and opening the circuit of relay 48, whose armature thereupon returns to normal. This does not affect relay 57 as its alternate circuit has already been completed, nor will it affect relay 61 since its holding circuit is independent of the key R.

The party at A now obtains connection with B as explained for an ordinary local call, informs him that he is wanted on the trunk line, and then replaces the receiver upon the switchhook. B now depresses trunk key T to way-down position, thereby releasing home key H (depressed in connecting with A), completing a circuit to operate the relay 48 as described for station A, and also completing a short circuit about the relay 61 to deenergize the latter. This short circuit extends from battery 18, conductors 19 and 67, bus bar 16, third contact of key T at station B, and conductors 68 and 69, resistance 71 (which prevents too great a flow of current over this circuit), and conductor 62 to the other side of battery. Deenergization of relay 61 opens its holding circuit and also the alternate circuit of the relay 57, which relay remains energized, however (the relay 48 having operated before the short-circuiting of relay 61), and prevents a disconnect signal being given at the exchange. The apparatus is now in the same condition as if B had answered the trunk call directly and conversation can now take place between B and the calling party.

Should any local station attempt to secure connection with another local station which is already connected with the trunk line, a single tap will be given by the signal 15 of the latter local station to inform the party thereof of such a call, but the other local station will not obtain a talking connection since the home button H of any station connected with the trunk line is in normal position.

On completion of a trunk conversation the parties would restore their receivers to their respective switchhooks, thereby in the usual manner deenergizing relay 48, and in turn opening the bridging connection between the

exchange end of the trunk through the relay 57. The disconnect signal at the exchange (not shown) is thereby operated to indicate that conversation had been completed and the operator withdraws her plug (not shown) from the jack 10, which connects the answering signal 11 across the line for future operation and restores the entire system to normal position.

20 What is claimed is:

1. In a telephone system in combination, a plurality of subscribers' stations, a telephone set at each of said stations, a source of talking current, an electromagnetic signal individual to each of said sets operated by direct current and having two windings, each interposed between a different pole of the source of talking current and a telephone set to serve as impedance means for talking current on establishment of a talking circuit between telephone sets of said system, and means to establish a talking circuit between telephone sets of said system including the two windings of the signal individual to one of the telephone sets connected by said talking circuit in said circuit as an impedance means for talking current supplied to said connected sets.
  - 15
  - 20
  - 25

2. In a telephone system, in combination,
30 a plurality of subscribers' stations, a telephone set at each of said stations, a source of talking current, an electromagnetic signal individual to each of said sets operated by direct current and having two windings,
35 each interposed between a different pole of the source of talking current and a telephone set to serve as impedance means for talking current on establishment of a talking connection between telephone sets
40 of said system, means to operate the signal at a called station, and means to establish a talking circuit between telephone sets of said system including the two windings of the signal individual to a called station of the telephone sets connected by said talking circuit in said circuit as an impedance means for current supplied to said connection.

3. In a telephone system, in combination,
50 a plurality of subscribers' stations, a telephone set at each of said stations, a source of talking current, an electromagnetic signal individual to each of said sets operated by direct current and having two windings,
55 each interposed between a different pole of the source of talking current and a telephone set to serve as impedance means for talking current on establishment of a talking connection between telephone sets of said system,
60 means to establish a talking circuit between telephone sets of said system including the two windings of a signal individual to one of the telephone sets connected by said talking circuit in said circuit as an
65 impedance means for current supplied to

said connected sets, and means to limit the signaling actuation of such signal subsequent to its inclusion in said talking circuit.

4. In a telephone system, in combination, 70
a plurality of subscribers' stations, a tele-
phone set at each of said stations, a source
of talking current, an electromagnetic signal
individual to each of said sets and operated
by direct current and having two windings,
each interposed between a different pole of
the source of talking current and a tele-
phone set to serve as impedance means for
talking current on establishment of a talk-
ing connection between telephone sets of 80
said system, means to operate the signal at a
called station, means to establish a talking
circuit between telephone sets of said sys-
tem including the two windings of the signal
individual to a called station of the tele-
phone sets connected by said talking cir-
cuit in said circuit as an impedance means
for current supplied to said connection, and
means to limit the signaling actuation of
such signal subsequent to its inclusion in 85
said talking circuit. 90

5. In a telephone system, in combination, a plurality of subscribers' stations, a telephone set at each of said stations, a source of talking current, an electromagnetic direct current signal at each of said stations having two windings, each interposed between a different pole of the source of talking current and a telephone set to serve as impedance means for talking current supplied to its station and said signal also including an interrupting device, an operating circuit for said signal interrupted by said device, means to establish a talking circuit between telephone sets of said system including said source of current and the two windings of the signal of one of the sets connected thereby in said talking circuit as an impedance means, and a shunt connection about the interrupting device of such signal completed on establishment of said talking circuit to prevent interruption thereof by said device. 95 100 105 110 115

6. In a telephone system, in combination, a plurality of subscribers' stations, a telephone set at each of said stations, a source of talking current, an electromagnetic direct current signal at each station having two windings, each interposed between a different pole of the source of talking current and a telephone set, an operating circuit for said signal, said signal including an interrupting device to open said circuit on energization of said signal and to close said circuit on deenergization thereof, means to establish a talking circuit between a pair of the telephone sets of said system including the source of current in the two windings of the signal of one of the sets connected by said talking circuit therein as an impedance means, and a shunt connection 130

about the interrupting device of the signal of the other of said connected sets completed on establishment of said talking circuit.

7. In a telephone system, in combination, 5 a telephone station, a telephone set at said station, a pair of line conductors comprising two ends inductively connected for association with said station, a normally open bridging connection across one end of said 10 pair, a relay having a plurality of windings and controlling said bridging connection, a local source of current, a second bridging connection across the other end of said pair including said source of current and having 15 a relay winding intermediate said source of current and each of said conductors, and a circuit including said relay and source of current established on telephonic association of said telephone set with said other end of 20 said pair to operate said relay.

8. In a telephone system, in combination, a telephone station, a telephone set at said station, a pair of line conductors comprising two ends inductively connected for association with said station, a normally open bridging connection across one end of said 25 pair, means operated on telephonic association of said telephone set with the other end of said pair to control said bridging connection, an alternative bridging connection to said first mentioned connection, and means to control said alternative bridging connection independent of the means controlling said first mentioned bridging 30 connection.

9. In a telephone system, in combination, a telephone station, a telephone set at said station, a pair of line conductors comprising two ends inductively connected for association with said station, a normally open bridging connection across one end of said pair, means operated on telephonic association of said telephone set with the other end of said pair to control said bridging connection, an 40 alternative bridging connection to said first mentioned connection, means to control said alternative bridging connection independent of the association of said telephone set with said other end of said pair, and means to disable the means to establish said alternative connection incidental to subsequent telephonic connection of said telephone set with said other end of said pair.

10. In a telephone system, in combination, 55 a plurality of telephone stations, a telephone set at each of said stations, a pair of line conductors comprising two ends inductively connected for association with any of said stations, a normally open bridging connection across one end of said pair, means operated on telephonic association of one of said telephone sets with the other end of said pair to control said bridging connection, an alternative bridging connection, means to 60 control said alternative connection independ-

ent of the association of any of said telephone sets with said other end of said pair, and means to disable the means to establish said alternative connection incident to subsequent telephonic connection of any of said 70 telephone sets with said other end of said pair.

11. In a telephone system, in combination, a telephone station, a telephone set at said station, a pair of line conductors comprising two ends inductively connected for association with said station, a normally open bridging connection across one end of said pair, means operated on telephonic association of said telephone set with the other end of said 75 pair to control said bridging connection, an alternative bridging connection to said first mentioned connection, and electromagnetic means to control said alternative bridging connection independent of the means controlling 80 said first mentioned connection.

12. In a telephone system, in combination, a plurality of telephone stations, a telephone set at each of said stations, a pair of line conductors comprising two ends inductively connected for association with any of said stations, a normally open bridging connection across one end of said pair, means operated on telephonic association of one of said telephone sets with the other end of said pair 90 to control said bridging connection, an alternative bridging connection, electromagnetic means to control said alternative connection independent of the means controlling said first mentioned connection, and means to 95 short-circuit said electromagnetic means incidental to subsequent connection of one of said telephone sets with said other end of said line.

13. In a telephone system, in combination, 105 a plurality of telephone stations, a telephone set at each of said stations, a pair of line conductors comprising two ends inductively connected for association with said station, a normally open bridging connection across one end of said pair, a relay included in said connection and operated on establishment thereof, switching means at each of said stations, electromagnetic means controlled by said switching means to establish said bridging connection, and a locking circuit for said 110 electromagnetic means established on operation of said relay.

14. In a telephone system, in combination, 120 a plurality of telephone stations, a telephone set at each of said stations, a pair of line conductors comprising two ends inductively connected for association with said station, a normally open bridging connection across one end of said pair, a relay included in said connection and operated on establishment thereof, switching means at each of said stations, electromagnetic means controlled by said switching means to establish said bridging connection, a locking circuit for said 125 electromagnetic means established on operation of said relay.

tromagnetic means established on operation of said relay, and means operated incident to subsequent association of a telephone set with said other end of said pair to disable said electromagnetic means.

15. In a telephone system, in combination, a plurality of telephone stations, a telephone set at each of said stations, a pair of line conductors comprising two ends inductively connected for association with said station, a normally open bridging connection across one end of said pair, a relay included in said connection and operated on establishment thereof, switching means at each of said stations, electromagnetic means controlled by said switching means to establish said bridging connection, a locking circuit for said electromagnetic means established on operation of said relay, means operated incident to subsequent association of a telephone set with said other end of said pair to disable said electromagnetic means, a second bridging connection across the same end of said pair as the first connection, and means to establish said second connection incident to subsequent association of the telephone set with said other end of said pair.

16. In a telephone system, in combination, a plurality of stations, a telephone set at each of said stations, a local signal at each of said stations, means to telephonically connect two of said stations, and means to operate the local signal of one of said connected stations during telephonic connection thereof incidental to the calling of such station by another of said stations without destroying the effective telephonic connection of the two connected stations.

17. In a telephone system, in combination, a plurality of stations, a telephone set at each of said stations, a local signal at each of said stations, means to telephonically connect a calling and a called one of said stations together, and means to operate the local signal of the calling of said connected stations during telephonic connection thereof incidental to the calling of said calling station by another of said stations without destroying the effective telephonic connection of the two connected stations.

18. In a telephone system, in combination, a plurality of local stations, a telephone set

at each of said stations, a local signal at each of said stations, the coils of which signal form an integral part of a telephone circuit when one of said stations calls and is connected with another station telephonically, a trunk line extending to one of said stations, means to telephonically connect such station with said trunk line, and means whereby the local signal of such station may be operated during telephonic connection thereof with said trunk line by another local station calling such station.

19. In a telephone system, in combination, a plurality of local stations, a telephone set at each of said stations, a local signal at each of said stations, the coils of which signal form an integral part of a telephone circuit when one of said stations calls and is connected with another station telephonically, a trunk line adapted to be connected with one of said stations, means to telephonically connect said station with said line, a talking circuit established between said station and said line on operation of said connecting means, and a signaling circuit distinct from said talking circuit to operate the local signal at said station during talking connection of said station and line, whereby interference between said circuits is prevented.

20. In a telephone system, in combination, a plurality of local stations, a telephone set at each of said stations, a trunk line leading to the central office station adapted to be telephonically connected with one of said stations, a signal circuit, means at other of said local stations adapted to complete said circuit, a local signal at such station adapted to be included in said circuit and including a circuit interrupting means normally operable to interrupt said circuit during actuation of said circuit completing means, and means to provide a shunt path about said interrupting means on connection of such station with said trunk line whereby said interrupting device is inoperative to interrupt said signal circuit on actuation of said circuit completing means during connection of such station with said trunk line.

In witness whereof, I hereunto subscribe my name this 18th day of March, A. D., 1918.

CHARLES W. KECKLER.
